UNITED STATES PATENT OFFICE.

CHARLES F. MILLER, OF CHICAGO, ILLINOIS, ASSIGNOR, BY DIRECT AND MESNE ASSIGNMENTS, TO CHICAGO SHOE MACHINERY COMPANY, OF CHICAGO, ILLINOIS, A CORPORATION OF ILLINOIS.

AUTOMATIC PRESSER-FOOT MECHANISM FOR LEATHER-STITCHING MACHINES.

Application filed March 16, 1921. Serial No. 452,676.

To all whom it may concern:

Be it known that I, CHARLES F. MILLER, a citizen of the United States, residing at Chicago, in the county of Cook and State of Illinois, have invented certain new and useful Improvements in Automatic Presser-Foot Mechanism for Leather-Stitching Machines, of which the following is a specification.

10 This invention relates to new and useful improvements in wax thread leather stitching machines generally, but more specifically to an automatic presser foot mechanism therefor.

15 One of the principal objects of the invention is to provide a presser foot with means for automatically locking the same against movement during the greater portion of a cycle and for releasing said locking means 20 during the lesser portion of the cycle, whereby the work will be firmly clamped against the work support by the presser foot during the penetrating movement of the awl, and whereby said presser foot will be released during the work-feeding stroke of 25 the awl.

Another object of the invention is to provide manual means for releasing said locking means and raising the presser foot at 30 any time during the cycle, whereby the work may be inserted or withdrawn.

Another object of the invention is to provide a cam-controlled mechanism for intermittently actuating the locking mechanism.

35 A still further object of the invention is to provide a locking mechanism and a co-operating manual means for releasing this locking mechanism.

In the drawings, 40 Figure 1 is a side elevation showing my improved presser foot mechanism,

Figure 2 is a detail elevation with the adjustable disk removed,

45 Figure 3 is a rear view of the adjustable disk,

Figure 4 is a detail sectional view taken on the line 4—4 of Figure 2,

50 Figure 5 is a view similar to Figure 1, but showing the manual means shifted to release the locking mechanism.

Like reference numerals designate corresponding parts in all the figures of the drawings.

Referring to the drawings, 5 designates

the main shaft of the machine, on which is 55 fixed a cam 6, having a peripheral notch 7 formed therein.

Disposed in spaced relation to the cam 6 is a work support 8 on which the work 9 is adapted to be clamped by a presser foot 10. This presser foot is in the form of an arm fulcrumed on a shaft 11, the center of the shaft being indicated at 12. Fixed on the shaft 11 is a brake lever 13, having a convexed outer end 14, which is adapted to co- 65 operate with the concaved face 15 of a brake shoe 16. A roller carrying lever 17 is pivoted at its lower end, as at 18, to the frame 19 of the machine, and carries at its upper end a roller 20 which is adapted to alternately 70 engage the concentric portion 21 of the cam disk 6 and the notch 7 thereof. The lever 17 is pivoted between the cam disk 6 and the brake shoe 16 and is movable in a direction towards and from said brake shoe. A link 75 22 has one end pivoted, as at 23, to the roller-carrying lever 17 at a point above the pivot 18 thereof, and has its other end connected to the brake shoe 16 by a pivot pin 24.

80 From the above, it will be seen that when the roller 20 rides into the notch 7, the lever 17 will be moved to the left, and, consequently, the link 22 and the brake shoe 16 will be bodily moved in the same direction, thus withdrawing the brake shoe from 85 cooperative relation with the convexed brake surface 14 of the presser foot lever 13.

When the presser foot is in its co-operative position, the pivot 24 will be below a straight line drawn through the pivot 23 and the center 12 of the presser foot supporting shaft 11. This, in effect, constitutes a toggle link, so that any upward movement of the pivot 24 will necessarily clamp the 90 brake shoe 16 against the presser foot lever 13, and thereby lock said presser foot 10 against movement. When, however, the roller 20 rides into the notch 7, as above described, the pivot 24 and brake shoe 16 95 will be moved towards the left and out of contact with the presser foot lever 13, thereby releasing the locking mechanism for the presser foot.

100 In order to support the pivot 24, and also to provide means for manually releasing said presser foot locking mechanism, I have provided a manually operable hand lever 25,

which is provided at its lower end with a head 26. The head 26 is, in turn, journaled on a boss 27 formed on the frame 19. The head 26 is provided in its outer face with 5 a circular seat 28, which is eccentrically arranged with respect to the pivot boss 27. Formed on the inner face of the seat 28 is a series of outwardly projecting and radially disposed ribs 29, which co-operate with a 10 series of radially disposed ribs 30 formed on the inner face of a disk 31. The head 26 is held on the boss 27 by means of a screw 32, and the disk 31 is held in position by a screw 33. The ribs 29 and 30 co- 15 operate to retain the disk 31 against movement relative to the operating lever 25. These ribs, however, permit the disk 31 to be axially adjusted and retained in an adjusted position. A link 34 has its upper 20 end pivoted, as at 35, to the disk 31, and has its lower end fulcrumed on the pivot 24.

A locking pawl 36 passes through a suitable opening formed in the head 26 and is adapted to engage a notch 37 formed in the 25 periphery of the boss 27, and thereby lock the operating lever 25 in its normal or inoperative position. The pawl 36 is connected by a link 38 to a hand lever 39, which is, in turn, pivoted, as at 40, to the operating 30 lever 25. A spring 41 is disposed between the main lever 25 and the hand lever 39, and serves to retain the latter in its normal position.

Fixed to the head 26 of the operating lever 35 is an arm 42 having a cam-shaped nose 43 adapted to engage a forwardly extending pin 44, which is fixed to the presser foot 25 lever 13.

A spring 45 has its lower end connected 40 to the presser foot lever 13 by a screw 46 and has its upper end connected to the frame of the machine by a screw 47. This spring normally exerts an upward pull on the presser foot lever 13, and tends to yieldingly hold the presser foot 10 in engagement 45 with the work 9.

When it is desired to release the locking mechanism and raise the presser foot 10 from off the work, the hand lever 39 is 50 drawn towards the operating lever 25 to release the pawl 36 from its engagement with the boss 27. Continued movement of the operating lever 25 in the same general direction, that is, towards the right, will 55 cause the cam-shaped nose 43 to be moved downwardly and into engagement with the pin 44. This movement will also move the pivot 35 of the link 34 and thereby cause the pivot 24 to be moved further below a 60 line passing through the pivot 23 and the center of the presser foot supporting shaft 11. Upon continued movement of the operating lever 25, the presser foot lever 13 will 65 be swung around the shaft 11, thereby raising the presser foot 10, as clearly shown in

Figure 5 of the drawings. When it is desired to return the parts to their normal or locked positions, the operator merely pushes the operating lever 25 to its initial position, shown in Figure 1. This movement returns 70 the brake shoe 16 into co-operative locking engagement with the presser foot lever 13 and also permits the locking pawl 36 to be seated in the retaining notch 37, thus locking 75 the presser foot against movement.

Inasmuch as the concentric surface 21 of the cam 6 is considerably longer than the notch 7, the presser foot will be held in its locked position for the greater portion of each cycle, and will be released during the 80 smaller portion of each cycle.

By axially adjusting the disk 31, the link 34 and pivot 24 will be bodily shifted towards or from a line extending through the center 12 and the pivot 23, thereby varying 85 the effective positions of the brake lever 13 and the brake shoe 16.

Another important feature of my invention, resides in the peculiar construction of the presser-foot per se, which, by reference 90 to Fig. 1 of the drawings, it will be seen is provided on one of its sides with a pair of spaced and laterally extended arms or projections 48 and 49. The space between these arms is for the reception and operation 95 of the curved needle of the machine as it oscillates.

By thus constructing the presser-foot the needle will be shielded from the uppers of 100 the shoes while the sewing is being done thereon, thus preventing the said uppers getting in the way of or being pierced by the needle, and besides, this arrangement permits the stitching of the soles to be performed when the shoe is presented upside 105 down to the work support or when presented in the reverse manner.

What I claim is:

1. In a leather stitching machine, the combination with a work support, of a pivoted presser foot co-operating therewith, a brake-lever fixed to said foot, cam-controlled means including a brake-shoe frictionally co-operating with said brake-lever for locking the foot against pivotal movements during the greater portion of each cycle and for releasing said locking means during the lesser portion of each cycle, and means for varying the position of said shoe with respect to said brake-lever.

2. In a leather stitching machine, the combination with a work support, of a pivoted presser foot co-operating therewith, a brake-lever fixed to said foot, a cam, means controlled by the cam including a link-supported brake-shoe frictionally co-operating with said brake-lever for locking the foot against pivotal movements during the greater portion of each cycle and for releasing said locking means during the 130

lesser portion of each cycle, and means for varying the position of said shoe with respect to said brake-lever.

3. In a leather stitching machine, the combination with a work support, of a pivoted presser foot co-operating therewith, a brake-lever fixed to said foot, a cam, a lever fulcrumed on a fixed pivot, a roller carried by said lever and co-operating with 10 said cam, a brake-shoe frictionally co-operating with said brake-lever, and a link pivotally connected to said roller-carrying lever and to said brake-shoe, and means for varying the position of said shoe with respect to said brake-lever.

4. In a leather stitching machine, the combination with a work support, of a pivoted presser foot co-operating therewith, a brake-lever fixed to said foot, a cam, a lever fulcrumed on a fixed pivot, a roller carried by said lever and co-operating with 20 said cam, a brake-shoe co-operating with said brake-lever, a link pivotally connected to said lever and to said brake-shoe, and a 25 supporting link for said brake-shoe pivotally connected to the last mentioned link.

5. In a leather stitching machine, the combination with a work support, of a pivoted presser foot co-operating therewith, 30 a lever fixed to said foot and having a convexed brake-engaging end, a cam having a notch formed in its periphery, a lever disposed between said presser foot lever and said cam and fulcrumed at its lower end 35 on a fixed pivot, a roller carried by the upper end of said lever for engagement with the periphery and notch of said cam, a brake-shoe having a concaved surface for engagement with the convexed brake-engaging end of the presser foot lever, and a 40 link having one end pivotally connected to the roller-carrying lever at a point above the fulcrum thereof and having its other end pivotally connected to said brake-shoe.

45 6. In a leather stitching machine, the combination with a work support, of a pivoted presser foot co-operating therewith, a brake-lever fixed to said foot, and cam-controlled means including a brake-shoe 50 co-operating with said brake-lever for locking the foot against pivotal movements during the greater portions of each cycle and

for releasing said locking means during the lesser portion of each cycle, said brake-lever and said brake-shoe being respectively formed with convexed and concaved engaging faces, and a supporting link for 55 said brake-shoe pivotally connected to the last mentioned link.

7. In a leather stitching machine, the combination with a work support, of a pivoted presser foot co-operating therewith, a brake-lever fixed to said foot, a cam, means controlled by the cam including a link-supported brake-shoe co-operating with 60 said brake-lever for locking the foot against 65 pivotal movements during the greater portion of each cycle and for releasing said locking means during the lesser portion of each cycle, and a spring for yieldingly urging 70 the presser foot towards the work support.

8. In a leather stitching machine, the combination with a work support, of a pivoted presser foot co-operating therewith, 75 a brake-lever fixed to said foot, a cam, a lever fulcrumed on a fixed pivot, a roller carried by said lever and co-operating with said cam, a brake-shoe co-operating with 80 said brake-lever, a link pivotally connected to said lever and to said brake-shoe, a manual means co-operating with said presser foot lever for raising said foot, and a supporting link for the brake-shoe pivotally connected to said manual means. 85

9. In a leather stitching machine, the combination with a work support, of a pivoted presser foot co-operating therewith, a brake-lever fixed to said foot, a pin carried by said brake-lever, a cam, a lever fulcrumed on a fixed pivot, a roller carried by 90 said lever and co-operating with said cam, a brake-shoe co-operating with said brake-lever, a link pivotally connected to said lever and to said brake-shoe, a manually 95 operable lever fulcrumed on a fixed pivot for engagement with the pin carried by the brake-lever upon movement of said lever in one direction, an axially adjustable disk carried by said lever, and a link having one 100 end pivotally connected to said brake-shoe and the other end pivotally connected to said adjustable disk.

CHARLES F. MILLER.
